MEANS FOR FLOWING FLUIDS UNDER
PRESSURE

Jeddy D. Nixon, Houston, Tex., assignor of one
half to Wilson Supply Company, Houston, Tex.
a corporation of Texas

Application May 5, 1938, Serial No. 206,101

24 Claims. (Cl. 103—232)

This invention relates to new and useful improvements in means for flowing fluids under pressure.

One object of the invention is to provide certain improvements in the means set forth in my co-pending applications Serial No. 241,040 filed November 17, 1938 and Serial No. 239,348 filed November 7, 1938.

The foregoing means involved metering or reducing the pressure fluid and utilizing it at a reduced pressure to supply the full fluid pressure to the work until the working or flowing pressure was built up to overcome the said reduced pressure; however, in each instance heads of pressure were accumulated in confined areas.

Both of the foregoing applications set forth apparatus wherein the full pressure of the working or lifting fluid was applied to the controlling element, which in the first application was a metering valve and which in the second application was a time controlled needle valve. While these two elements operated to meter the flow of the pressure fluid (gas), the entire apparatus was subjected to a more or less high fluid pressure and some difficulty was experienced in regulating the apparatus so that a uniform operation was obtained. Further, owing to the comparatively large volume of pressure fluid accumulated and the metering of the fluid from one container to another, whereby the pressure was considerably reduced, moisture in the pressure fluid, particularly condensation, caused freezing and impeded the operation. While both of the apparatuses operated, they were not fully satisfactory in all respects.

Because of the foregoing, the instrumentalities employed were more or less complicated, cumbersome, or scattered and more or less floor space and room was required to accommodate the apparatuses.

One object of the invention is to provide an improved apparatus wherein the accumulation of high pressure fluid is eliminated and the controlling step is performed under low pressure.

A further object of the invention is to provide an improved apparatus wherein no quantities of pressure fluid are accumulated and freezing is eliminated.

An important object of the invention is to provide a control mechanism which will be much more simple and compact than those heretofore employed, and wherein the time controlled actuating valve will be subjected only to the low working pressure of the mechanism.

Still another object of the invention is to pro-

vide apparatus wherein a small quantity of the high pressure fluid is by-passed at low working pressure and intermittently released to control the flow of the working fluid at a low pressure and the supply thereof to the actuating mechanism.

An important object of the invention is to provide an apparatus wherein a low pressure actuating fluid is by-passed around a spring loaded supply valve and applied against said valve to maintain a predetermined low pressure; together with means for intermittently applying the by-passed pressure fluid to a spring loaded feed valve to feed the actuating fluid at low pressure to means for admitting the supply of high pressure fluid to the work, in combination with a release valve arranged to be actuated by the flowing pressure of the fluids being flowed to release the low pressure actuating fluid and operate said last named means to cut off the supply of high pressure fluid.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a view, partly in elevation and partly in section, showing an apparatus constructed in accordance with the invention, parts of the elements being illustrated as broken to condense the view;

Figure 2 is an enlarged, upright view of the control mechanism or unit, partly in elevation and partly in section;

Figure 3 is an enlarged, vertical sectional view of the control valve block;

Figure 4 is a side elevation of the control unit and its stand;

Figure 5 is an enlarged, vertical sectional view of the feed valve;

Figure 6 is a view of the release valve, partly in section and partly in elevation;

Figure 7 is a plan view of the apparatus applied to a well, the derrick being in section and parts being omitted; and

Figure 8 is an enlarged, vertical sectional view of the supply valve.

In the drawings the numeral 10 designates the well head (Figures 1 and 7) which is mounted on the casing 11 and supports the tubing 12. The usual liquid or well column flow line 13 extends from the tubing between the head and a stuffing 55

box 14. As the mechanism above the stuffing box is substantially the same as the mechanism shown in my co-pending application Serial No. 241,040, and is subject to variation, it will not be described in detail.

As set forth in my co-pending applications, a lifting fluid under high pressure, for instance from 250 pounds to 1000 pounds, per square inch, is supplied from a suitable source through a pipe 15 to the head 16. This lifting fluid flows into the casing 11 and its admission to the tubing 12 in the well, may be controlled by an actuator 86' operating a wire line 88, as is fully explained in my co-pending application, Serial No. 241,040.

15 A reduced pipe 16 is connected with the high pressure fluid supply pipe 15 and leads to a control unit 17 (Figures 1, 2 and 4). The unit includes a housing 18 mounted on a stand 19 which is securely fastened to the derrick floor 20. The housing has a hinged cover on its front side. The base of the stand 19 is comparatively small, so that the unit occupies little floor space and the housing is elevated so as to be readily accessible.

Referring to Figures 1 and 2, it will be seen 25 that the pipe 16 enters the lower left hand side of the housing 18 and connects to a supply or regulator valve A. A pipe 21 leads across the bottom of the housing (Figure 2) from the valve A, and has connected therein a feed valve B, which is located at the center of the bottom of the housing 18. A continuation 22 of the pipe 21 extends uprightly in the housing and in turn connects to a further horizontal extension 23, which is carried laterally through the right side wall of the housing. The pipe 21 and its extensions 22 30 and 23 will be hereinafter referred to as the feed pipe, as will also any further extensions connected thereto.

40 A four-way coupling 24 is connected in the extension 23 and has mounted on its upper side a relief valve C, while a release valve D is connected to the underside of said coupling. The valves A, B and D are of the spring loaded, diaphragm type, the valve A being shown in detail in Figure 8, while the valve B is fully illustrated in Figure 5. The valve A has a by-pass, which will be hereinafter described, so that the pressure fluid metered through the seat 26 of said valve is applied at a low pressure on top of the diaphragm 27 to close the valve in opposition to the spring 28 which tends to open the valve.

45 The by-passed pressure fluid is also supplied to a tube 29 which leads to a control valve E similar to the valve in my co-pending application, Serial No. 239,348, and this valve is operated by a time controlled device F, such as is shown in said application all of which is hereinafter fully described. A tube 30 leads from the valve E, and when the latter is opened, supplies the by-passed 50 pressure fluid to the diaphragm 31 of the valve B to open the same in opposition to its closing spring 32. From the foregoing, it will be seen that by reducing the pressure of the by-passed fluid to a pressure much less than the operating pressure, the control valve E and its time controlled device F, operate against a low pressure and a more uniform control and regulation may be had.

55 The feed pipe extension 23 is connected by a pipe 85 with the actuator 86'. When the valve E is opened by the time mechanism, the valves A and B are opened, and the reduced pressure fluid flowing through the valve A will be conducted by the feed pipe to the actuator 86', which is operated to lift the wire line 88 and any suitable 60 element (not shown) connected thereto in said

tubing. When the piston (not shown) in the actuator reaches the upper end of its stroke, the lifting fluid in said casing 11 is admitted into said tubing 12 to lift the well fluid, as in my above mentioned co-pending applications. As the pressure in the actuator, the feed pipe and its extensions, the valves A and B and on top of the diaphragms 27 and 31 is built up, the valve A is closed against the action of the spring 28 and further flow through the valve A and the feed pipe will be terminated and consequently, the pressures in the unit will be balanced, whereby the valve E will drop to a closed position. The valve B is then closed which will trap the low pressure fluid in the feed pipe and the actuator 86' and maintain said actuator in its upper position, as in the aforesaid applications. Further description will be given of the details and variations.

65 The well pipe 13 is connected with a pipe 33 which enters the bottom of the housing and applies the flowing pressure of the fluids being discharged from the well, against the diaphragm 34 of the valve D to open said valve in opposition to its closing spring 35. A pressure release pipe 36 extends from the valve D through the right hand side of the housing 18. When the flowing pressure reaches a predetermined degree, the valve D is opened and vented to the atmosphere, whereby the pressure fluid trapped in the feed pipe and in the actuator is released. The release is gradual owing to the small size of the pipe 36 and the pet cock 71 for controlling the escape of said pressure fluid therethrough, so that the actuator is slowly lowered to cut off the admission of high pressure fluid from said casing to said well tubing.

70 Referring to Figures 2 and 8, it will be seen that the valve A is provided with a tubular stem 26' having its lower end tapered for engaging in the metering seat 26. Just above this seat, the stem is provided with a port 37 which communicates with the bore or passage 38 of said stem, whereby a portion of any fluid metered through said seat enters the bore 38 of said stem. This stem 26' extends upwardly through a hanger or support 39 for the spring 28 and a piston or disk 40 is screwed on to the upper portion of said stem adjacent the underside of the diaphragm 27, which is fastened in the housing 41. It is pointed out that the upper end of said spring 28 bears against the underside of the disk, as shown in Figure 8. The disk 40 is supported by and sustains the compression of the spring 28 which rests upon the hanger 39. The hanger is adjustable, whereby the compression on the spring 28 may be varied. The stem also extends up through said diaphragm and receives a nut 42, whereby said diaphragm is securely clamped to the disk 40. A T-coupling 43 is connected in the top of the housing 41 and in turn is connected to the tube 29. The housing 41 is supported by a pair of upright standards 44 extending from the valve A.

75 A suitable pressure gage 45 may be mounted on the T-coupling 43. The spring 28 is set to open the valve A by lifting the valve stem sufficiently to admit a restricted flow of fluid through the seat 26. The feed valve B being closed, the pressure fluid will fill the pipe 21 between the valves A and B and enter the bore of the stem 26' by way of the port 37, whereby it will be by-passed to the housing 41 and flow into the tube 29 up to 80 the valve E. When sufficient fluid has accumulated above the diaphragm 27 to overcome the spring 28, said diaphragm will be depressed and the valve A thus closed. The by-passed pressure fluid is thus trapped above the dia- 85

phragm, in the pipe 21 and the bore 38 of the stem. Should this trapped pressure at any time leak out, the spring 28 will open the valve A and replenish the same.

5 The valve B, shown in detail in Figure 5, is of somewhat similar construction to valve A and the same reference numerals will be used to designate like parts. The valve has a small seat 46 through which the stem 46' passes. This stem carries a valve head 47 having a flat underside of considerable more area than the seat 46, and provided with a beveled shoulder engaging the underside of the seat for closing the same. The flat underside of the head 47 offers sufficient area to the pressure below said head, that such pressure may assist in seating said valve against a like or even greater pressure above said seat.

10 The stem 46' is attached to the diaphragm 31, which is depressed to open the valve B against the compression of the spring 32. It is pointed out 15 that the valve A is sprung opened, while the valve B is sprung closed. The tube 30 has one end fastened to the top of the housing 41' of the valve B. Whenever the valve E is open, the pressure 20 trapped in the tube 29 and in the housing 41 of the valve A flows into the tube 30 and depresses the diaphragm 31, whereby the valve B is opened and pressure fluid is then permitted to flow 25 through the feed pipe 21, 22, 23 and 25. This opening of the valve E causes a pressure drop 30 above the diaphragm 27 of the valve A, whereby the latter is opened and additional fluid will enter the system from the pipe 16 to build up the pressure in the feed pipe, the actuator 86', tubes 29 and 30, valves A and B, housings 41 and 41' and the bore 38 of the stem 28'.

35 The valve E, as shown in Figures 2 and 3, includes a valve block 50 having a thimble 51 screwed into its bottom for attaching the tube 29. A valve seat 52 is located above the thimble and at the bottom of an enlarged bore 53, substantially the same, as in my co-pending application Serial No. 239,348. The bore 53 extends to the top of the block 50 and has its upper end screw threaded to receive an elongated plug or bushing 54 which has an axial duct or bore 55 extending downwardly from its top to a counter bore or valve chamber 56.

40 A needle valve 57 housed in the valve chamber 56 is adapted to undergo a limited sliding movement therein and to engage the seat 52 and an elongate valve rod or stem 58 extending up through the duct 55 engages the upper end of the needle valve but has no fixed connection therewith. As will be seen in Figure 3, said needle valve 45 and the stem 58 each have a loose sliding fit in the valve chamber 56 and duct 55 respectively, so that the pressure fluid may seep therewith and escape from within the block 50. Manifestly, when said valve stem 58 is moved downwardly, its 50 lower end resting upon said needle valve, will move said valve downwardly so that its conical point engages in the seat 52 and closes the reduced port beneath said seat. So long as said stem is 55 in its lowermost position, it will hold said valve in a seated position, which will positively prevent a flow of fluid from the pipe 29 into the bore 53. When the pressure on the upper end of said valve stem is released or reduced, the pressure of the 60 fluid in the pipe 29 acting against the underside of said valve will move said valve and said stem upwardly in the chamber 56 and duct 55. It is noted that the upward movement of said valve 57 will be limited by the upper end of said valve 65 striking the upper end of said chamber and as this

upward movement ceases, the upward movement of the valve stem will also terminate. The bore 53 also has a lateral port 61 receiving a thimble 61', whereby the tube 30 is connected to said block. When the valve E has been opened and 5 the valve B also opened, the pressure of the fluid in the tubes 29 and 30 will be reduced and the fluid by seeping along the valve 57 and stem 58 will further reduce this pressure, permitting the valve A to open and supply sufficient pressure fluid to 10 operate the actuator 86' and maintain the predetermined pressure desired in the unit.

15 The timing device F and control mechanism associated therewith is the same as in my aforesaid application. The timing device consists of a 15 suitable time clock (not shown) mounted in a housing 75 and having a driving shaft 76 extending therefrom through the housing and clock wheel 62 is mounted on said shaft so as to revolve therewith. A small roller 77 for riding on the 20 periphery of the wheel 62 is journaled in the upper end of an upright arm 78, which has a swing connection with a horizontally disposed lever 79 pivoted in one corner of the block 50. Due to its pivotal mounting, the lever 79 tends to swing 25 downwardly at all times and is supported only by the valve stem 58 (Figures 2 and 3) whereby the weight of said lever, said arm 78 and roller 77 is imposed upon said stem and said needle valve 57 to hold the latter in its seated position. In 30 order for said needle valve to open, the pressure below said valve must be sufficient to lift said lever 79, said arm 78 and roller 77.

35 The clock wheel 62 has notches 80 cut in its periphery and as said wheel revolves in a counter-clockwise direction (Figure 2), said roller 77 riding on the periphery of said wheel will enter said notches, as said wheel revolves. It is pointed out that the spring 81 is adjusted so that when the roller is riding the periphery of said wheel between said notches, the needle valve will not be lifted off its seat by the pressure therebelow. However, when said roller enters one of said notches, the tension of said spring is reduced sufficiently so that the pressure of the fluid below 45 said needle valve will lift said valve 57, lever 79, arm 78 and roller 77, thereby permitting the pressure trapped in the pipe 29 to flow into pipe 30, into the cap 41', onto the diaphragm 31 and open the valve B. As the pressure equalizes in the 50 pipes 29 and 30, said needle valve 57 will drop to a closed position and the continued revolving of the clock wheel 62 will lock or hold said valve in its closed position. The pressure fluid in the pipe 30 will seep along the valve 57 and stem 58, and 55 as the pressure fluid in said pipe and the housing 41' is depleted, the valve B will gradually close. The pressure differential across the valve head 47 and the diaphragm 31 together with the tension of the spring 32 closes said valve B, which traps 60 the pressure fluid in the feed pipe 23 and the actuator until released by the opening of the valve D.

65 The valve D is shown in Figures 2 and 6 and includes a case 63 having an upstanding, tubular pin 64 which is externally screw threaded to receive a cap 65 into which the nipple 25 screws. The case 63 has a counterbore 66 with a seat 67 at its upper end. A stem 68 extends through said case and bore 66 and is provided 70 with a valve head 69, similar to the head 47, mounted on the upper end of the stem 68 and closes down onto the seat 67. A port 70 extends laterally from the bore 68 and the small release pipe 75 is connected therein, so that the release 75

of the pressure fluid from the feed pipe may be controlled and the piston (not shown) of the actuator 86', thus lowered at the desired rate of speed.

- 5 The diaphragm 34 of the valve D is supported in a housing 41" like the diaphragms 27 and 31 and the operating parts are the same as in the valves A and B. The pipe 33 conducting the well fluids under flowing pressure, is connected to the 10 valve housing 41", which is inverted with relation to the other valves, and thus the diaphragm 34 is moved upwardly to open the valve D against the combined closing action of the spring 35 and the pressure differential across the valve head 69. Whenever the pressure of the well fluids 15 builds up sufficiently to overcome the foregoing, the valve D will be opened. The pressure fluid in the lower portion of the valve B, the feed pipe 21, 22, 23 and 85, the actuator 86', the coupling 20 24, the nipple 25 and the valve D above the valve head 69 will be vented to the atmosphere through the pipe 36 and pet cock 71. The valve C includes a valve case 72 screwed into the coupling 24 and nipple 73 screwed into the upper end of the case 25 loosely confines a valve ball 74. When the valve B has been closed and the pressure fluid in said feed pipe and related structure is reduced, the valve ball 74 falls and opens the valve C so as to vent the feed pipe to the atmosphere. The 30 valve C is provided in case a small leak occurs in the valve B and thereby prevents the building up of a pressure in the feed pipe and the actuator, which would lift the piston (not shown) in the actuator, at a time not desired. It is pointed out that with the provision of the valve C, the 35 actuation of the actuator can be predetermined and regulated as desired. The valve C readily closes whenever a volume of pressure fluid enters the same, such as when the valve B is opened.
- 40 A complete cycle of operation of said apparatus is as follows: Normally the wire line 99 and the piston (not shown) of the actuator are at their lowermost positions. High pressure fluid is supplied from the pipe 15 (Figures 1 and 7) to the well casing 11 and the pipe 16 from which it flows into the supply valve A in the unit 17. The spring 28 normally holds the stem 26' off the seat 26 and the pressure fluid will be metered through said seat at a considerable reduction in 45 pressure and by-passed through the stem to the housing 41 above the diaphragm 27 and into the pipe 29, the valve E being closed. When the predetermined pressure has been built up, said diaphragm will be depressed and the valve A closed.
- 50 55 When the wheel 62 of the timing device F revolves to a point where the needle valve 57 (Figures 2 and 3) is released, the by-passed low pressure fluid in the pipe 29 will lift said valve and flow through the pipe 30 into the housing 60 41' onto the diaphragm 31 of the valve B, thereby opening said valve. When the valve E opens, a pressure drop will occur in the pipe 29 and above the diaphragm 27, so that the spring 28 will open the valve A. This will permit the pressure fluid to flow freely through the feed pipe 21 and its extensions 22, 23 and 85 to the actuator 86', whereby the piston therein will be elevated thus lifting the wire line 99 and admitting high pressure lifting fluid from the casing 11 to 70 the tubing 12 within the well.

When the piston in the actuator reaches its upper limit, the pressure of the fluid in the feed pipe, the valves A and B, the bore 38 of the stem 26', the housings 41 and 41', the pipes 29 and 30 75 and the valve E will build up until the valve A

is closed, at which time the flow of the pressure fluid through the feed pipe will be stopped. The valve E will then drop closed and the escape- 5 ment wheel 62 in time will revolve sufficiently to hold it closed. The valve B will gradually close, due to the escaping of the pressure fluid from 10 the pipe 30 by seeping around the needle valve 57 and its stem 58. The flat underside of the valve head 47 causes a pressure differential across the same, which will assist the spring 32 in the 15 closing of said valve. It is pointed out that the pressure within the unit at all times is a low pressure and does not go above the predetermined pressure at which the valve A is set to close.

The actuator will remain in its flowing or admitting position because of the pressure fluid trapped between it and the valve B. When the flowing pressure of the well fluids in the pipe 33 overcomes the combined force of the spring 35 and the pressure differential across the valve 69, 20 the valve D will be opened. This will release the trapped fluid from the pipe 21 through the bore 66, port 70, pipe 36 and pet cock 71. As the pressure in the pipe 21 reduces, the actuator will lower the wire line 99 and cut off the admission 25 of high pressure lifting fluid from the casing into the tubing.

It is pointed out that by metering the pressure fluid through the seat 26, relatively small quantities of such fluid at low pressure, may be used 30 and the control elements are not subjected to high fluid pressures. For this reason, a more accurate control may be employed and more uniform operation thus obtained. Further, no quantities of pressure fluid being accumulated, freezing is 35 eliminated and condensation is practically negative. The whole system may be quickly drained by removing a plug A' from the bottom of the valve A, and a similar plug B' from the bottom of the valve B. The apparatus is economical as 40 comparatively little pressure fluid is wasted.

What I claim and desire to secure by Letters Patent is:

1. A control unit for a fluid pressure flowing apparatus including, a high pressure fluid supply conductor, a supply valve having a metering seat for reducing the fluid pressure, a feed conductor extending from said valve, a feed valve connected in said feed conductor, means for actuating said supply valve, means for actuating said feed valve, means for by-passing a portion of the reduced pressure fluid to the actuating means of the supply valve, and means for intermittently supplying the by-passed fluid to the actuating means of the feed valve. 45

2. A control unit for a fluid pressure flowing apparatus including, a pressure fluid supply conductor, a supply valve having a metering seat for reducing the fluid pressure, a feed conductor extending from said valve, a feed valve connected 60 in said feed conductor, means for actuating said supply valve, means for actuating said feed valve, means for by-passing a portion of the reduced pressure fluid to the actuating means of the supply valve, means for intermittently supplying the 65 by-passed fluid to the actuating means of the feed valve, and a pressure fluid operated release valve connected with the feed conductor.

3. A control unit for a fluid pressure flowing apparatus including, a pressure fluid supply inlet, means for controlling the flow of fluid from said inlet at a reduced pressure, means for bypassing a portion of the pressure fluid at a reduced pressure from the inlet and utilizing such fluid to close the inlet, an automatic actuating 70 75

valve controlling the flow of the by-passed fluid, and means for controlling the flow of fluid from the inlet connected with said valve for actuation by the released by-passed fluid.

6 4. A control unit for a fluid pressure flowing apparatus including, a pressure fluid supply inlet, means for controlling the flow of fluid from said inlet at a reduced pressure, means for by-passing a portion of the pressure fluid at a reduced pressure from the inlet and utilizing such fluid to close the inlet, an automatic actuating valve controlling the flow of the by-passed fluid, means for controlling the flow of fluid from the inlet connected with said valve for actuation by the released by-passed fluid, means for conducting the pressure fluid from the inlet at a reduced pressure arranged to trap such fluid, and means for releasing the trapped fluid.

10 5. A control unit for a fluid pressure flowing apparatus including, a housing, a stand for supporting said housing, a fluid pressure inlet pipe entering said housing, a spring-loaded diaphragm supply valve in the housing connected with said pipe, a spring-loaded diaphragm feed valve mounted in said housing, a feed pipe extending through the housing from the supply valve and in which the feed valve is connected, the supply valve having a by-pass for conducting fluid to the upper side of its diaphragm, a control valve 15 having intermittently operating means, and means for conducting the by-passed fluid from the control valve to the upper side of the diaphragm of the feed valve.

20 6. A control unit for a fluid pressure flowing apparatus including, a housing, a stand for supporting said housing, a fluid pressure inlet pipe entering said housing, a spring-loaded diaphragm supply valve in the housing connected with said pipe, a spring-loaded diaphragm feed valve mounted in said housing, a feed pipe extending through the housing from the supply valve and in which the feed valve is connected, the supply valve having a by-pass for conducting fluid to the upper side of its diaphragm, a control valve 25 having intermittently operating means, means for conducting the by-passed fluid from the control valve to the upper side of the diaphragm of the feed valve, and a spring-loaded diaphragm release valve mounted in the housing and connected in the feed pipe.

30 7. A control unit for flowing fluids including, a fluid feed pipe, a fluid supply valve connected to one end of said pipe, a feed valve connected in the feed pipe, a fluid by-pass extending from one 35 valve to the other valve, and a control valve having means for intermittently opening and closing the by-pass connected in said by-pass from one valve to the other valve.

40 8. A control unit for flowing fluids including, a fluid feed pipe, a fluid supply valve connected to one end of said pipe, a feed valve connected in the feed pipe, a fluid by-pass extending from one valve to the other valve, a control valve having means for intermittently opening and closing the by-pass connected in said by-pass for controlling the flow of fluid through said by-pass from one valve to the other valve, a release valve connected in the feed pipe beyond the feed valve, and a vent connected to the feed pipe.

45 9. The combination with an actuator, of a feed pipe leading to said actuator to feed a pressure fluid thereto for operating said actuator, a supply valve connected to said pipe for supplying a pressure fluid thereto at a reduced pressure, a feed- 50 valve connected in the feed pipe for trapping the

pressure fluid between said actuator and the feed pipe, whereby said actuator is held in an adjusted position, means for by-passing a portion of the low pressure fluid to close the supply valve, automatically operated means for supplying said by-passed fluid to the feed valve to open the latter, and pressure operated means for releasing the pressure fluid trapped in the feed pipe to free the actuator.

5 10. A control device including, a fluid supply valve having a metering seat for supplying fluid at a reduced pressure and a spring pressed member engaging said seat, a diaphragm connected with said member for lifting it from said seat, means for by-passing fluid from a point above and adjacent said seat to the upper side of said diaphragm, and automatic means for controlling the by-passed fluid above said diaphragm to build up the pressure thereof to depress said diaphragm and close said valve and to release said by-passed fluid to permit the spring thereof to open said valve, in combination with a spring closed feed valve connected with the supply valve and having a diaphragm connected with the fluid release of said control means, whereby said diaphragm is 15 depressed to open the feed valve.

15 11. A control device including, a fluid supply valve having a metering seat and a spring pressed member closing on said seat, a diaphragm connected with the valve member for lifting it from 20 its seat, means for by-passing fluid from above said seat to the upper side of the diaphragm, automatic means for controlling the by-passed fluid above said diaphragm to build up the pressure of said fluid to close said valve and releasing said 25 pressure to permit the spring to open said valve, a spring closed diaphragm opened feed valve connected with the control means, and a conductor extending from the feed valve to the supply and communicating with the by-passing means for 30 by-passing fluid flowing through the feed valve to the upper side of the diaphragm of the supply valve and the control means.

35 12. A system of controlling the flow of fluid which includes, a flow conduit for supplying a fluid under pressure, means connected in said conduit for controlling the flow of said pressure fluid including means for by-passing a small quantity of said fluid at reduced pressure, means connected in the conduit and controlled by the 40 pressure of said by-passed fluid to feed said pressure fluid at a reduced pressure, and means for releasing the reduced pressure fluid.

45 13. A system of controlling the lifting of well fluid which includes, a well, a flow line in said well, a flow conduit for supplying a pressure fluid to said well to lift said well fluid, means for controlling the admission of pressure fluid to said flow line, means connected to said conduit for controlling the flow of the pressure fluid 50 including means for by-passing a small quantity of fluid at a reduced pressure, means connected in said conduit and intermittently actuated by the pressure of said by-passed fluid to control the flow of said pressure fluid admitted to said flow 55 line, and means connected to said flow line and said flow conduit and actuated by the pressure of the flowing well fluid for building up a pressure and arranged to release and reduce the pressure of said pressure fluid in the flow conduit 60 to cut off the flow of said pressure fluid to said admission controlling means.

65 14. A system of controlling the lifting of well fluid which includes, a well, a flow line in said well for providing a column of well fluid, means 70

75 valve connected in the feed pipe for trapping the

- for supplying pressure fluid to said well, means for controlling the admission of pressure fluid to said column of well fluid, means connected to said supply means for by-passing a reduced quantity of pressure fluid, means connected to said by-passing means for intermittently controlling the flow of a portion of said reduced quantity of pressure fluid, means for conveying said reduced quantity of pressure fluid to operate said admission controlling means, and means connected to said flow line and actuated by the pressure of the flowing well fluid for building up a pressure differential between said intermittently controlled fluid and the pressure of said well fluid
- 15 and arranged to release and reduce the pressure of said intermittently controlled pressure fluid, whereby the admission of said pressure fluid to said column of well fluid is cut off.
16. A system of controlling the lifting of well fluid which includes, a well, a flow line in said well for providing a column of well fluid, means for supplying a pressure fluid to said well, means for controlling the admission of pressure fluid to said column of well fluid, means connected to said supply means for segregating a reduced quantity of pressure fluid, means connected to said segregating means for intermittently controlling the flow of a portion of said reduced quantity of pressure fluid, means for conveying said reduced quantity of pressure fluid to operate said admission controlling means, means connected to said flow line and actuated by the pressure of the flowing well fluid for building up a pressure differential between said controlled fluid and the pressure of said well fluid and arranged to release and reduce the pressure of said controlled pressure fluid to cut off the admission of said pressure fluid to said column of well fluid, and means connected to said intermittent means for timing the controlling of said portion of the reduced quantity of pressure fluid to control the frequency of admission of said pressure fluid to said column of well fluid.
17. A system of controlling the lifting of well fluid which includes, a well, a flow line in said well for providing a column of well fluid, means for supplying a pressure fluid to said well, means for controlling the admission of pressure fluid to said column of well fluid, means connected to said supply means for intermittently by-passing a small quantity of said pressure fluid at a reduced pressure to set up a pressure differential for a predetermined period of time to actuate the pressure fluid admission controlling means for said column of well fluid to flow said well fluid, means connected to said by-passing means for cutting off the by-passing of said small quantity of reduced pressure fluid without terminating the admission and flowing of said pressure fluid to said well fluid, and means connected to said flow line and actuated by the pressure of the flowing well fluid for building up a pressure differential between said reduced pressure fluid and said well fluid and arranged to cut off the admission of said pressure fluid to said column of well fluid.
18. In a well fluid control apparatus the combination with a well and a flow line in said well for providing a column of well fluid and means for admitting pressure fluid to said column of well fluid and means for supplying pressure fluid to the point of admission to said column and an actuator for controlling said admission means, of a conductor for conveying said pressure fluid from said pressure fluid supply means, means connected in said conductor for regulating the flow of pressure fluid from said conductor and for reducing the pressure of the same, a conduit extending from said regulating means to said actuator, means connected in said conduit for cutting off the flow of pressure fluid through said conduit to control the operation of said actuator, means for by-passing a portion of said pressure fluid from said regulating means to said cut-off means to actuate both said regulating means and said cut-off means, a time control device for terminating the flow of said by-passed fluid from said regulating means to said cut-off means, and means for releasing the reduced pressure fluid from said conduit after said cut-off means thereof has been closed.
19. In a well fluid control apparatus the combination with a well and a flow line in said well for providing a column of well fluid and means for admitting pressure fluid to said column of well fluid and means for supplying pressure fluid to the point of admission to said column and an actuator for controlling said admission means, of a conductor for conveying said pressure fluid from said pressure fluid supply means, means connected in said conductor for regulating the flow of pressure fluid from said conductor and for reducing the pressure of the same, a conduit extending from said regulating means to said actuator, means connected in said conduit for cutting off the flow of pressure fluid through said conduit to control the operation of said actuator, means for by-passing a portion of said pressure fluid from said regulating means to said cut-off means to actuate both said regulating means and said cut-off means, a time control device for controlling the flow of said by-passed fluid from said regulating means to said cut-off means, and means connected to said conductor and actuated by the pressure of the flowing well fluid for building up a pressure differential between said reduced pressure fluid and the pressure of said well fluid and arranged to release said reduced pressure fluid to cut off the admission of pressure fluid to said column of well fluid.
20. A control unit for a pressure fluid flowing apparatus including, a pressure fluid supply pipe, means for regulating the flow of fluid through said pipe at a reduced pressure, means for by-passing a portion of the pressure fluid from the pipe and utilizing such fluid to close said pipe, an automatic valve controlling the flow of the by-passed

5 fluid, and means connected in said pipe beyond said regulating means for controlling the flow of fluid through the pipe and actuated by the released by-passed fluid from said valve; said control unit being mounted on the surface of a well having a casing, a tubing in the casing, means for supplying pressure fluid to said casing, and means including pressure fluid actuated means for controlling the admission of fluid from said 10 casing into said tubing to lift the fluid in said tubing, said control unit regulating the delivery of pressure fluid to said pressure fluid actuated means to control the operation of said admission controlling means.

15 21. A control unit for a pressure fluid flowing apparatus including, a pressure fluid supply pipe, means for regulating the flow of fluid through said pipe at a reduced pressure, means for bypassing a portion of the pressure fluid from the pipe and utilizing such fluid to close said pipe, an automatic valve controlling the flow of the by-passed fluid, and means connected in said pipe beyond said regulating means for controlling the flow of fluid through the pipe and actuated by the released by-passed fluid from said valve; said control unit being mounted on the surface of a well having a casing, a well tubing in the casing, means for supplying pressure fluid to said casing, means including pressure fluid actuated means 20 for controlling the admission of fluid from said casing into said tubing to lift the fluid in said tubing, said control unit regulating the delivery of pressure fluid to said pressure fluid actuated means to control the operation of said admission controlling means.

25 22. A control unit for a pressure fluid flowing apparatus including, a pressure fluid supply pipe, means for regulating the flow of fluid through said pipe at a reduced pressure, means for bypassing a portion of the fluid from the pipe and utilizing such fluid to close said pipe, an automatic valve controlling the flow of the by-passed fluid, and means connected in said pipe beyond said regulating means for controlling the flow of fluid through the pipe and actuated by the released by-passed fluid from said valve; said control unit being mounted on the surface of a well having a casing, a tubing in the casing, means for 30 supplying pressure fluid to said casing, means

including pressure fluid actuated means for controlling the admission of fluid from said casing into said tubing to lift the fluid in said tubing, said control unit regulating the delivery of pressure fluid to said pressure fluid actuated means to control the operation of said admission controlling means, and time-controlled means on said control unit for regulating the actuation of said automatic valve to control the operation of said unit.

35 23. A control unit for flowing fluid including, a fluid feed pipe, a fluid valve connected to said pipe to control the flow of fluid into said pipe, a flow control valve connected in the feed pipe beyond the fluid valve, a fluid by-pass extending from one valve to the other valve, a control valve having means for intermittently opening and closing the by-pass, the fluid flowing through said by-pass actuating said flow control valve; said control unit being mounted on the surface of a well having a casing therein, a well tubing in the casing, means for supplying pressure fluid to said casing, and means including pressure fluid actuated means for controlling the admission of fluid from said casing into said tubing to lift the fluid in said tubing, said control unit regulating the delivery of pressure fluid to said pressure fluid actuated means to control the operation of said admission controlling means.

40 24. A control unit for flowing fluid including, a fluid feed pipe, a fluid valve connected to said pipe, to control the flow of fluid into said pipe, a flow control valve connected in the feed pipe beyond the fluid valve, a fluid by-pass extending from one valve to the other valve, a control valve having means for intermittently opening and closing the by-pass, the fluid flowing through said by-pass actuating said flow control valve; said control unit being mounted on the surface of a well having a casing therein, a well tubing in the casing, means for supplying pressure fluid to said casing, means including pressure fluid actuated means for controlling the admission of fluid from said casing into said tubing to lift the fluid in said tubing, said control unit regulating the delivery of pressure fluid to said pressure fluid actuated means to control the operation of said admission controlling means, and clock-actuated means on said control unit for regulating the actuation of said automatic valve to control the operation of said unit.
